SIMPLIFIED ARTILLERY MECHANISM

Robert D. Gebeau, Bridgeport, Conn.

Application March 7, 1941, Serial No. 382,238

1 Claim. (Cl. 89—2)

This invention relates to guns designed for sustaining fire over extended periods of time, such, for example, as anti-aircraft guns and machine guns.

An important object of my invention is to provide a gun of the above character which is so constructed and arranged to avoid overheating of the firing chamber. According to the preferred form of my invention, this object is accomplished by the provision of means for continuously feeding shells individually enclosed within shell blocks into the firing chamber of the gun, automatically firing the shells and utilizing the resulting recoil for ejecting the shell blocks containing the exploded shells from the firing chamber.

The invention has as a further object to provide in a gun of the above character electrical means for firing the shells and means for utilizing the recoil action of the gun for automatically making and breaking the electrical firing circuit.

Another object of my invention is to provide in a gun of the above character improved means for feeding shell blocks into the firing chamber of the gun and for ejecting shell blocks containing the exploded shells therefrom.

Still another object of my invention is to provide a gun of the above character which is simple in construction, reliable in operation, and which is capable of rapid and economical manufacture by quantity production methods.

Other objects and advantages will be apparent from the following detailed description of a preferred embodiment of the invention, reference being had to the annexed drawings in which:

Figure 1 is a longitudinal cross-sectional view through a gun of the anti-aircraft type when in firing position;

Figure 2 is a view of the gun corresponding to Fig. 1, but showing the parts of the firing mechanism in recoil position;

Figure 3 is a transverse cross-sectional view through the gun on the line 3—3 of Fig. 1;

Figure 4 is a perspective view of a shell and shell block; and

Figure 5 is a longitudinal cross-sectional view of the rear end of the gun, showing the means employed for conditioning the gun for use.

In the drawings is illustrated an anti-aircraft gun supported upon a suitable mount M and comprising a barrel 1 extending from a casing 2, the casing being of generally rectangular shape in transverse cross-section (see Fig. 3), shrunk onto the breech of the barrel so as to form a unitary extension thereof. The bore 1a of the

barrel may be rifled (not shown) in accordance with usual practice. The casing 2 projects beyond the breech of the barrel so as to define a firing chamber C. Adapted to occupy this firing chamber is a shell block 3 containing a shell S, as will be later more fully described. The portion of the casing extending beyond the barrel provides a housing for a strong coil spring 4, the end of this housing being closed by an end wall 2a. The spring exerts pressure between the end wall 2a and a firing block 5 slidably disposed within the casing.

Shell blocks 3 are adapted to be introduced into and removed from the firing chamber C through inlet and outlet openings 6 and 7 provided respectively in the top and bottom walls of the casing but located in vertically offset relation. The forward travel of the shell block under the urge of the spring-biased firing block 5 is limited by engagement with the end of barrel 1, in which position both the inlet and outlet openings are closed by the firing block as shown in Fig. 1. When the shell is exploded in the firing chamber, the recoil throws the firing block and shell block rearwardly, against the action of the coil spring, to the position shown in Fig. 2, uncovering both the inlet and outlet openings.

As illustrated in Fig. 4, the shell block 3 comprises a rectangular core of steel 3a tightly expanded into a jacket 3b of a light metal, such as aluminum alloy. The core is centrally provided with a recess 3c of such size as to freely receive a shell S, the rim of the shell fitting within a countersink 3d formed in that end face of the shell block which is designed to abut the firing block 5 when the shell block is in the firing chamber. The corners of the shell block are preferably rounded to insure an easy fit within the firing chamber.

For feeding the shell blocks into the firing chamber the following mechanism is provided: Arranged upon the top wall of the casing 2 is a magazine 8 conforming substantially to the cross-section of a shell block, but extending rearwardly from a position overlying the inlet opening 6 to a position adjacent the lower or rear end of the casing 2. One end of the magazine is open to receive a series of shell blocks arranged in end-to-end abutting relationship, so that this train of shell blocks may be slid forwardly through the magazine as indicated in Fig. 1. Overlying the inlet opening 6 is a spring clip 9 having an upright section 9a by means of which the clip is anchored to the casing 2, and which additionally serves as a stop to limit the forward

movement of a shell block and positions it in registry with the inlet opening 6. Forming a lateral extension of the upper end of the upright section 8a is a tongue 8b so shaped as to be engaged by a shell block and lifted from the lowered position of Fig. 2 to the raised position indicated in Fig. 1, so as to bear against the upper face of the shell block and urge it through the inlet opening 6. When the firing block and shell block are driven to recoil position, as illustrated in Fig. 2, the shell block carrying the exploded shell is arrested by a stop lug 10 (indicated in phantom lines in Fig. 1) in a position immediately overlying the outlet opening 7 through which the shell block drops freely by gravity, assisted by a kicker spring 11. The shell block emerging from the outlet opening falls into a chute 12 from which it is directed into a receiving hopper, not shown.

The automatic firing mechanism of the gun comprises an insulated conductor 13 extending through a channel in the firing block 5, this conductor being connected at one end to a contact plate 14 inserted in the lower face of the firing block 5, and at its other end to a firing cap 15 disposed flush with the forward face of the block in registry with the shell recess 8c provided in the shell blocks 8. A companion contact plate 14a is secured within the lower wall of the casing 2, so as to engage the contact plate 14 when the firing block occupies the firing position shown in Fig. 1. Both contact plates 14 and 14a are suitably insulated from the rest of the gun structure. The gun structure forms a ground for the other side of the electrical circuit, and a cable 16 leads between a source of electrical energy (not shown) and the contact plate 14a. A trigger control switch T is connected in circuit with the gun for controlling the operation of the gun.

When the gun is first set in operation with no shell block 8 in the firing chamber, it is necessary to retract the firing block 5 against the action of coil spring 4, so that a shell block may be fed by the spring clip 9 from the magazine 8 into the firing chamber. This is accomplished as follows: The end wall 2a of the casing 2 is formed with a centrally disposed passage 17 which upon the interior of the casing is surrounded by a cylindrical sleeve 18 integral with the end wall. This sleeve is internally threaded for a portion of its length, the passage normally being closed by a screw-threaded plug 19 engaging the threads upon the sleeve.

Upon removing the plug 19 by means of a handle 20 formed thereon, a threaded rod 21 may be inserted through the passage 17 and screwed into a threaded opening 22 provided in the firing block 5, as shown in Fig. 5. Upon the outer end of the rod lying exteriorly of the end wall of the casing 2 is secured a handwheel 23 for conveniently rotating the rod in screwing it into the firing block. Surrounding the rod 21 and internally provided with screw threads for engaging the threads of the rod is a collar 24, this collar fitting within a smooth bored section of passage 17. By rotating the collar by means of a handwheel 25 provided upon the outer end thereof, the rod 21 is moved outwardly drawing with it the firing block 5 against the pressure of coil spring 4. When the firing block reaches the position shown in Fig. 2, a shell block 8 is fed from the magazine into the firing chamber. Then by unscrewing and removing the rod 21 and replacing the plug 19 in the passage 17, the

gun is in condition for firing, and such firing can be initiated by operating the trigger switch T.

It is believed that the operation of the gun just described will be apparent from the foregoing description. After conditioning the gun for operation in the manner just described and upon closing the switch T, a current of electricity will flow through the cable 16 and between the superposed contact plates 14 and 14a to the firing cap 15 to detonate the shell 8 carried within the shell block 8 occupying the firing chamber. The explosion of the shell produces a reaction which forces the shell block, and through the shell block the firing block 5, rearwardly breaking the connection between the two contact plates 14 and 14a. In the fully retracted position illustrated in Fig. 2, the shell block containing the exploded shell is arrested by the stop lug 10 immediately in registry with the outlet opening 7, through which opening this shell block drops under the influence of gravity aided by the kicker spring 4.

In this recoil position of the gun, the inlet opening 6 is clear to permit a shell block to be forced into the firing chamber, under the urge of clip 9, in advance of the retracted firing block 5, as that when the firing block containing the exploded shell drops through the outlet opening 7, the firing block is free to move forwardly under the urge of coil spring 4 into contact with the newly admitted shell block. When the firing block is restored to the position shown in Fig. 1, the contact plates 14 and 14a ride into engagement with each other and again close the firing circuit to explode the bullet in the shell block.

This cycle of loading, firing and discharge continues as long as the trigger control switch T remains closed, and so long as shell blocks are supplied to the magazine. Because the heat generated by explosion of the shells is largely absorbed by the shell blocks in which they are enclosed, and since the shell blocks are removed from the gun immediately after firing of the shells, the firing chamber is not subject to overheating after sustained periods of fire, such as constitutes a serious difficulty in rapid fire guns at present known to the art, and which overheating in many cases produces excessive expansion of the parts and results in jamming of the firing mechanism.

It will be apparent that the gun is of comparatively simple construction, and capable of rapid and economical manufacture. Manifestly the invention may be embodied in automatic guns of various sizes, including small arms. Instead of the means for feeding shell blocks from the magazine into the firing chamber described in connection with the foregoing embodiment of my invention, any other suitable type of shell feeding mechanism may be employed.

It should be understood that it is not desired to limit the invention to the exact details of construction herein shown and described, for obvious modifications within the scope of the claim may occur to persons skilled in the art.

I claim:

A continuous-fire single barrel gun adapted to fire metal-jacketed shells enclosed in rectangular heat-absorbing shell blocks, said gun comprising a casing defining at its forward end a firing chamber and being of rectangular shape in transverse cross section so as to accommodate the shell block, a barrel extending outwardly from the forward end of the casing, an inlet opening

through the upper wall of the casing adjacent its forward end, a magazine upon the casing adapted to guide a train of shell blocks into alignment with the inlet opening, means for feeding shell blocks individually from the magazine into the casing, a firing block slidable within the casing, a spring for urging said firing block into engagement with a shell block to normally insert and retain the shell block in the firing chamber, an outlet opening through the lower 10

wall of the casing rearwardly of the inlet for removal of the exploded shell blocks from the casing, a firing cap on the firing block in registry with a shell carried by the firing block, an electrical circuit including said firing cap, and a pair of sliding contacts on the firing block and the casing adapted to be intermittently moved into and out of circuit closing engagement upon reciprocation of the firing block.

ROBERT D. GEBEAU.
